AIR CONDITIONING APPARATUS

Ruddell J. Byrd, Irving, Tex.

Application March 29, 1935, Serial No. 13,621

11 Claims. (Cl. 261—92)

This invention relates to air conditioning and has for one of its principal objects to accomplish a more perfect temperature and humidity control than has heretofore been attained by air conditioning apparatus. Another main object is to provide for effectively cleaning and circulating the air confined in compartments, rooms, office and other buildings, and to make practically available a comfort and health promoting service in any season of the year and under any and all conditions where an air conditioning system is desirable and can function.

In the accompanying drawings forming part of this specification and illustrating practical adaptations of the invention,

Figure 1 is a vertical sectional view of an assembled machine showing the correlated parts, some more or less conventionally, the line of section being substantially the line 1—1 of Figure 2;

Figure 2 is a view, partly in end elevation, and partly in transverse section on the line 2—2 of Figure 1;

Figure 3 is a fragmentary section, on an enlarged scale, taken substantially on the line 3—3 of Figure 1;

Figure 4 is a perspective view, showing, in horizontal section, the bottom portion of the water chamber or tank element;

Figure 5 is a fragmentary sectional view illustrating a variable speed driving device, more or less conventionally, for operating the rotor which carries the air conditioning vanes;

Figure 6 is a cross section of a modified form of rotor, the section being taken on the line 6—6 of Figure 7;

Figure 7 is a side elevation of the rotor illustrated in Figure 6, the major portion of the peripheral covering fabric and interior vanes being removed to show the longitudinal cage bars which support the peripheral end portions of the vanes and the peripheral covering fabric;

Figure 8 is a fragmentary longitudinal section through the water chamber or tank, showing the frame of the rotor as rotatably mounted with relation to the chamber or tank, said rotor being of the type in which the peripheral supporting bars for the vanes and peripheral covering fabric are diagonally or spirally disposed, an illustrative diagram of the flow of the air stream through and about the rotor being indicated by the upper set of arrows, and the circulation of the water in the chamber or tank being indicated by the lower set of arrows;

Figure 9 is a fragmentary detail view of a preferred form of pipe for the refrigerating coils;

Figure 10 is a cross section of a further modification of the rotor, the section being taken on the line 10—10, of Figure 11;

Figure 11 is a view of the rotor illustrated in Figure 10, the major portion of the peripheral covering fabric and interior vanes being removed to expose the frame structure.

Passing air to be conditioned, as is the practice in some systems, through a bank of refrigerated coils and permitting the air to come in direct contact with the coil surface which, of necessity, is operated at a temperature below the dew point temperature, results in a constant reduction of the water content or humidity of the conditioned air until the danger point is reached in many instances. Systems that have been used in an attempt to check this disadvantageous action have mostly fallen far short of the required efficiency. So, too, various valves and regulators, devised in an attempt to govern the temperature of the coil surface so as to retard undue de-humidification of the conditioned air from appliances and systems heretofore used, have proven to be only slightly effective.

In cases where attempts have been made to introduce moisture by the use of sprays or the application of water in any form, the result has been to build up a foggy or excessively moist condition in the air stream discharged into the enclosure to be air conditioned, producing a bank of air always present around the apparatus and containing free water, which, though absorbed by the air in the enclosure in time, is constantly replaced and maintained by the fresh discharge from the apparatus.

The apparatus covered in the present disclosure differs materially from any devised heretofore, and in performance overcomes all of the foregoing noted objections. The present invention provides for the practical and efficient utilization of water as a heat gathering and conveying medium, while at the same time holding the water very effectually within its carrying elements so that no free water can escape, thereby placing the water, however, so as to be available for evaporation when conditions are favorable therefor, as when the air to be conditioned becomes dry or deficient in humidity and requires moisture. To this end, provision is made for the ready determination of certain balances in the apparatus to have the effect of automatically retarding or advancing the evaporation point by the functioning of the apparatus and

its relation to the water-carrying ability of the air at various temperatures.

Generally stated, the apparatus of the present invention involves the use of air conditioning surfaces dipped or washed at predetermined intervals in a bath of water which is heated or cooled, as the case may be, according to the season of the year and climatic conditions. The apparatus further indicates a bank or battery of refrigerating coils of a capacity to place them in proper balanced relationship with the area of the air conditioning surfaces employed in order that they may absorb the heat units gathered by the air conditioning surfaces and delivered by them to the water in which the coil bank or battery is submerged, the function of the coils, therefore, being to maintain a predetermined temperature in the water used, either above or below the dew point, as desired. Obviously, a motor and compressor of corresponding capacity with relation to the capacity of the aforesaid coils is provided.

The invention also comprehends the use of a thermostat in connection with the refrigerating coils and controlling the operation of the compressor to maintain a constant water temperature at a desired degree; an insulated water chamber or tank so designed as to contain the water and coils described herein and adapted for the collection, precipitation and discharge of sludge and impurities accumulated as taken from the air passing through the apparatus; an automatic water control means for maintaining a constant or substantially even water level in the water chamber or tank; heating elements submerged in the water to advance evaporation when that is desired; heating elements placed in the air stream to warm the air when warm conditioned air is desired; a fan or blower installed for the purpose of producing and maintaining a forced flow of air ideally over the air conditioning surfaces and through the apparatus, and discharging the conditioned air with greater velocity from the apparatus; a humidistat placed at any convenient location in the enclosure being air conditioned and so connected with the apparatus to automatically time its action when in use as a humidifier and air washer; a thermostat placed at any effectual point in the enclosure in which the apparatus is functioning as an air cooler, to prevent a drop in temperature below a comfortable or desirable point; an air filter; and a means for circulating the water over the heating or cooling elements described herein, thereby maintaining an even temperature throughout the body of water employed and facilitating the removal from the air conditioning surfaces or heat units, dust and objectionable matter or particles gathered on said surfaces during their exposure in the air stream through the apparatus.

The invention further includes a novel provision and arrangement of electric switches and controlling devices, and also water valves to control all elements individually and collectively in the make-up of the apparatus.

The use of air conditioning surfaces dipped or washed at predetermined intervals in a bath of water held at a predetermined temperature for air conditioning, embodies the advantage of a more satisfactory humidity control, the controlled temperature of the water providing a means for imparting to the air conditioning surfaces any desired temperature applicable ideally to air conditioning purposes. When this tem-

perature is set below the dew point of air at a given temperature and relative humidity, the air conditioning surfaces will gather moisture, thereby functioning as a de-humidifier and cooler. However, when de-humidification, set up by this process, has resulted in drying the air and retarding the dew point to that below the temperature of the air conditioning surfaces, the surfaces being damp, a reverse action is set up and moisture is imparted to rather than taken from the air stream.

The air conditioning surfaces being dipped or washed in the temperature controlled water at predetermined periods tend to balance the humidity at a desired point, because the air conditioning surfaces on leaving the bath and moving into the air stream immediately start to warm up and may, as an example, arrive at the dew point of the air stream when one-half of the allotted time of exposure to the air stream has elapsed, in which case the same surface that has been gathering moisture will give off moisture during the latter half of its exposure to the air stream, thereby balancing its influence on the humidity content of the air treated, but, at the same time, gathering heat units for the entire duration of the exposure.

The length and area of the air conditioning surface and the speed at which the air is passed over the surface also has a direct influence on the humidity content of the discharged air from the apparatus, as these are the factors in determining the length of time each unit of air is exposed to the conditioning surface. For example, a high air speed over a long or large surface may have exactly the same result as a low air speed over a short or relatively small surface. From this explanation it is seen that the function of the apparatus and the results attained are directly dependent on the predetermined engineering practice and balance built into the apparatus. A perfect cooperation with the law of nature is an inherent feature of an apparatus in accordance with the present invention and almost any desired result can be attained by a simple arrangement of balances as herein described, which will effectively and efficiently cool, warm, humidify, de-humidify, wash, clean, and circulate air to any desired degree within the range of air conditioning requirements.

The heating elements may be used separately or together, while the cooling elements are inactive, and inversely, the cooling elements may be used without the heating elements; and the air washing and circulating elements can be used while said other elements are inactive. Therefore, an air conditioning service is produced which is applicable to any condition and in any season of the year, or for many different chemical and manufacturing processes where air conditioning is necessary or desirable.

Referring now to the drawings, the numeral 1 designates generally the outer casing or cabinet of the apparatus. As shown, the cabinet 65 is lined throughout with insulation material 2. A horizontal partition 3 divides the interior of the cabinet into two separate compartments 4, 5, respectively.

In the lower compartment 5 is located the motor 6 and compressor 7 of an ordinary mechanical refrigerator unit, which being of any obvious construction and arrangement and control is merely shown conventionally.

In the upper compartment 4, adjacent one

end thereof, is a water chamber or tank 8. Submerged in the lower part of the chamber or tank 8 are refrigerating coils 9 which are connected at one end to the outlet of the compressor 7 by 5 a pipe 10, and at the opposite end to the intake of the compressor through a pipe 11. Where the pipe 10 joins the coils 9, it is provided with the usual expansion valve 12, and connected to said valve 12, through a small pipe 13, is a 10 thermal valve 14, said valves 12 and 14, cooperating with other controlling elements (not shown, because obviously provided in refrigerating units) to automatically stop operation of the motor and compressor when the temperature 15 of the coils drops to a predetermined degree for which the thermal valve 14 is set.

As shown in Figure 3, the chamber or tank 8 has heating elements 15 therein, said elements being submerged in the water in the tank and of 20 any suitable construction electrically for the purpose. They are, therefore, only illustrated conventionally, and the circuit wires 16 may be connected to any suitable switch (not shown), as these heaters are only used occasionally or as 25 necessary, and when used or not used the switches are operated manually to either close or open the respective circuits, as the case may be.

At the top of the chamber or tank 8 are bearing standards 17 in which a shaft 18 is journalled. 30 Mounted on said shaft 18 is a rotor 19 comprising annular peripheral members 20 at each end, said members 20 being connected by spokes or spider members 21 to hub members 22. The hub members 22 are connected by longitudinal cage bars 35 23, while the outer annular members 20 are connected by bars 24. In the form of the rotor shown in Figures 1, 8 and 11, which is the preferred form and arrangement, the bars 23 and 24 are diagonally or spirally disposed, for a purpose 40 to be later more fully described. In the modification shown in Figure 7, said bars 23 and 24 extend in substantially true parallel relation to the axis of the rotor shaft.

In the form of the rotor illustrated in Figures 1, 45 2, and 3, vanes or blade members 25 are provided of absorbent fabric, which, as shown, is a continuous strip or elongated sheet folded alternately about an adjacent pair of the outer cage bars 24 and re-entrantly about a single inner 50 cage bar 23, thereby producing, in effect, a series of radial vanes. Around the outside of the bars 24 is placed a cylindrical covering 26 of absorbent fabric. In this connection, it may be here noted that the said absorbent fabric is preferably material such as the character of terry cloth or similar pile fabric in which the loops are uncut, more particularly such material as so-called Turkish towels and wash cloths are made of. However, as 55 far as the present invention is concerned, various absorbent sheet materials or cloths may be used.

On the end of the shaft 18 is a suitable pulley 27 which is belted, as at 28, to a pulley 29 on a variably geared driving shaft 30 from an electric 60 motor 31. The motor 31, conventionally shown, may be of any approved type, as also may be the variable gearing for the shaft 30. However, gearing of the disk and roller type is preferably used and so illustrated in the drawings and somewhat 65 in detail in Figure 5, in which a disk 32, fixed on the main shaft 33 of the motor 31 and located in a housing extension 34, has a roller 35 in frictional contact therewith, whereby to be rotated upon rotation of the disk, yet it is slidably longitudinal of its axis, across the face of the disk, 70

by a shipper element 36 which has cross arms 37 slidably mounted in guide openings in a flanged extension 38 of the housing extension 34. Said shipper element 36 has an operating rod 39 attached thereto, as at 40, the outer end portion of the rod extending out through a guide opening in the wall of the cabinet 1 and having a suitable knob or handle member 41 on its outer end. 5

The roller 35 is fixed on a spindle member 42, having an annularly grooved collar 43 at its end, 10 with which collar a bifurcated end portion 43a of the shipper element cooperatively engages. This spindle member 42 is fitted slidably in an axial bore 44 in the shaft 30, said shaft having a longitudinal groove 45 in which a key member 15 or spline 46 on the spindle member 42 is slidably fitted, whereby the spindle member is freely movable endwise but locked to rotate with the shaft 30. By manipulating the rod 39, moving it endwise, the roller 35 is selectively moved towards or 20 from the axis of the disk 32, whereby the speed of the roller is varied, at will, when it is desired to change the speed of the rotor 19.

In the top of the cabinet 1, near the end opposite to that at which the rotor is located, is an 25 outlet opening 47 for the conditioned air discharged from the apparatus. This opening is preferably covered by a perforated plate or suitable grille 48. Beneath the perforated plate or grille 48 is an upwardly flared or substantially 30 inverted truncated pyramidal casing 49, at the bottom of which is a housing 50, the upper portion of which is generally rectangular in form and the lower portion being semi-cylindrical. In opposite ends of the housing 50 openings 51 are provided, and journalled in bearings 52 on said ends of the housing, centrally of said openings 51, is a shaft 53 on which is fixed a centrifugal blower fan (not shown, because it may be of any approved construction), which, when rotated, draws 40 air into the housing 50 through said openings 51 and forcibly discharges it through the upwardly flared casing 49 and out through the perforated plate or grille 48 of the opening 47. 35

On the shaft 53 of the blower fan, outside of 45 the housing 50, is a pulley 54 which is belted, as at 55, to a pulley 56 on the main shaft 33 of the motor 31 (see Figure 2), by which arrangement the motor drives the blower fan simultaneously with rotor 19. 50

In the casing 49 is a series of heating elements 57, of any suitable or approved electrical type, said elements being merely conventionally shown and the terminal wires 58, in practice, are connected to a suitable switch (not shown), whereby 55 said elements may be energized and de-energized, at will, when it is desired to heat the conditioned air passing out of the apparatus, or not, as will be later more fully explained.

In the use of the apparatus it is preferable to 60 place a thermostat 59 at any convenient and effectual point in the compartment, room, or enclosure to be air conditioned; also, a humidistat 60; and have each electrically connected, as at 61, to a part of the electrical controlling circuit 65 of the motor 31, whereby either, or both the thermostat 59 and the humidistat 60, may be set to operate at a given degree of temperature or humidity, as the case may be, and thereby automatically break the motor circuit and stop operation of the 70 motor when the temperature or humidity comes to a degree below or above that for which the particular instrument is set. In this connection, it may be here noted that the thermostat 59 is ordinarily used only in the summer season or dur- 75

ing relatively warm periods, while the humidistat 60 is ordinarily used only during the winter season. That is to say, in the summer season, when the cooling agency or refrigerating coils 9 are used, 5 the humidity is regulated naturally by the balanced relation of the temperature of the water in the chamber or tank 8, the length and area of the air conditioning surfaces of the rotor 19, and the speed of the air stream through the apparatus. In the summer season, however, the thermostat is 10 set for a degree of minimum temperature, and as long as the temperature in the enclosure being air conditioned is above that minimum the apparatus continues to operate, but as soon as that minimum is reached the thermostat operates to 15 automatically stop the motor 31.

The temperature of the refrigerated water in the chamber or tank 8 is also automatically regulated so as not to fall below a predetermined degree. This is governed by the thermal controlling 20 valve 14 and associated elements (not shown) of the refrigerating units 6, 7, as hereinbefore described, but not, per se, a part of the present invention and only entering into the invention in a broad and general sense.

30 The cooling coils 9 may be of any approved type, but, for better distribution of the refrigerating agency, the pipes are preferably provided with circumferential annular fins or flanges 62, as illustrated in Figure 9 of the drawings.

35 In order to heat the water at such times when it is desired to advance vaporization thereof and, of course, when the refrigerating coils 9 are not used, in the winter season under certain conditions, or when the apparatus is used in enclosures 40 where a certain chemical laboratory or manufacturing process or some physical process is carried on, requiring air conditioning, the hereinbefore described heating elements 15 may be utilized to advantage.

45 Preferably, the vanes 25 of the rotor 19 are disposed in the diagonal or substantially spiral arrangement as shown in Figures 1, 8 and 11, by which arrangement, the portion of the rotor rotating submerged in the water in the chamber or tank 8 not only moves the water laterally but imparts an endwise movement thereto, causing a circulation forwardly near the top of the body of water, thence downwardly and rearwardly near the bottom of the chamber or tank and upwardly 50 at the rear of the rotor, as indicated by the lower set of arrows in Figure 8. This positive circulation of the water carries the entire body of water into contact with the refrigerating coils, thereby maintaining an even temperature throughout the body 55 of water. This particular arrangement also causes a more positive contact of the air stream with the vanes as it is drawn through the rotor by the suction of the blower fan in the housing 50.

60 As the rotor rotates in the water in the chamber or tank 8, the particles of dust, lint and other matter taken by the vanes 25 from the air stream passing through the rotor, as well as such taken by the peripheral cylindrical absorbent cover 26, is washed off in the form of sludge which precipitates to the bottom of the chamber or tank 8. In order to catch and trap the sludge the bottom of the chamber or tank is accordingly depressed, as at 63, and preferably formed hopper-bottom-like, with a general incline toward one end, as shown 65 more clearly in Figures 2 and 3.

As a means for flushing the bottom of the chamber or tank 8, to clear it of accumulated sludge, at frequent intervals, it is preferable to provide the water inlet of the chamber or tank with an arcuate perforated manifold or nozzle head 64, 5 so that, as presently more fully described, when the water is admitted under pressure to the chamber or tank it washes across the bottom 63 from its higher side to its lower side, at which latter side a drain outlet 65 is provided, said water inlet 10 and said drain outlet being each controlled by electrically controlled valves which are normally closed while the water in the chamber or tank 8 is at a predetermined level and both opening automatically and simultaneously when the water falls below such level. 15

Communicably attached to the inlet manifold or nozzle head 64 is a supply pipe 66 from a suitable source of water supply under pressure, either normal city water pressure or pressure created specially for the purpose, according to the place of installation of the apparatus. In this pipe 66 is an electrical valve 67 (not shown in detail), preferably of the type that opens under the water pressure in the direction of flow, or self-opening, 20 but closed by a solenoid when energized. The drain outlet 65 has a pipe extension 68 which connects, as at 69, with a vertical overflow pipe 70 extending up into an auxiliary tank 71 communicating with the water chamber or tank 8 25 through an opening 72. In the pipe 68 is a valve 73, similar to the valve 67, and, as just above stated, these two valves are either closed or open, both at the same time, and they are operated simultaneously to open or closed condition. 30

In the auxiliary tank 71 is a float element 74, mounted on the lower end of a rod 75 slideable vertically through a guide bracket 76 located on the wall of the cabinet and having its upper end operably connected to a switch element 77, which latter engages a terminal element 78 of the switch 79. The terminal element 78 is electrically connected to a wire 80 from a service line of electricity, while the movable switch element 77 is connected by a wire 81 and the wires 82, 83, respectively to one terminal 84 of the valve 67 and one terminal 85 of the valve 73 (see Figure 2). The other terminals 86, 87, respectively, of the valves 67 and 73, are connected by wires 88, 89, to a wire 90 back to the service line. 45

When the water in the auxiliary tank 71 reaches a level whereby the float element 74, through its rod 75, lifts the movable switch element 77 into engagement with the switch terminal element 78 of the switch 79, the electrical circuit for the two valves 67, 73, is closed and the solenoids thereof are energized, thereby effecting the closing of said valves. When the water level drops appreciably in the auxiliary tank 71, the float element 74, of course, drops accordingly and the switch element 77 is disengaged from the terminal element 78 of said switch 79, thereby breaking the circuits of the valves 67 and 73, and said valves automatically open. Obviously, the overflow pipe 70 is at all times open and the water is prevented 55 from reaching higher than a predetermined level in the main water chamber or tank 8 and the auxiliary tank 71. 60

It may be here noted that the drain outlet is of sufficient area to readily drain off the sediment 70 washed from the bottom of the chamber or tank 8 by the discharge from the manifold or nozzle head 64, but at the same time the water entering through the manifold or nozzle head is under pressure and in sufficient volume to fill the tank more 75

rapidly than the drain takes off the contaminated water at the bottom of the chamber or tank 8. In this way, as frequently as water is taken into the chamber or tank 8 to replenish its normal bulk, the sludge is at the same time washed out through the drain.

In the modification of the rotor 19 as illustrated in Figures 10 and 11 there is an intermediate ring member 91 in its end frame, with longitudinal bars 92 mounted thereon. Radial vanes 93 are attached to the inner bars 23 on the hub members 22 and every fourth outer bar 24 on the peripheral ring member 20, while attached to the two intermediate outer bars 24, between said 10 fourth bars, and to the bars 92 on the ring member 91, between said vanes 93, are pairs of vanes 94 in outwardly diverging or substantially V-shape relation. This arrangement of the vanes provides increased air conditioning surface with ample 15 space for the passage of the air through the rotor, and in this modification the vanes are disposed diagonally or spirally, longitudinally of the rotor, as in the form of rotor illustrated in Figures 20 1 and 8 of the drawings.

1 and 3 of the drawings.

25. A further modification of the rotor is illustrated in Figures 6 and 7, wherein the vanes 95 are radiated from every third inner bar 23 to every fourth outer bar 24, while from the intermediate and alternate single inner bars 23 to the two intermediate outer bars 24, between said fourth bars, are pairs of vanes 96 in outwardly diverging or substantially V-shape arrangement. In this modification the vanes 95 and 96 extend directly longitudinally of the rotor and parallel with the

30. 35 axis of the rotor.

An arched or semi-cylindrical hood 97 is preferably placed over the water chamber or tank 8, thereby providing a tunnel in which the rotor operates and through which the air stream is drawn by the blower fan into the housing 50. This hood extends to the end wall of the cabinet 1 (see Figure 1), and a screen 98 is preferably provided at the air inlet 99 of the cabinet so that the air is filtered as it enters the cabinet. This screen, of course, is removable for the purpose of cleaning it from time to time or replacing it with another screen, as well as to gain access to the adjacent inner portion of the cabinet, as occasion may require.

50 The apparatus herein illustrated and described, in all of its modifications, performs all the functions herein described and through its use is attained a better temperature and humidity control in air conditioning than heretofore accomplished
55 in such field of endeavor.

Obviously, the apparatus admits of further modification than herein specifically shown and described without in the least departing from the spirit and scope of the invention as defined in the appended claims. The invention, therefore, is not limited to the specific construction and arrangement of apparatus illustrated in the accompanying drawings.

What is claimed is:

65 1. An air conditioning apparatus which comprises a rotor covered with absorbent material and having spiral vanes of said material, a tank containing liquid within which the rotor dips, thereby moistening said surfaces, means located in said tank for raising and for lowering the temperature of the liquid therein, means for drawing air through the rotor in contact with said moistened absorbent surfaces, and positive means for imparting rotation to said rotor, said rotation causing circulation of the liquid to in-

70

75

sure uniformity of temperature through the body of the liquid.

2. An air conditioning apparatus comprising a liquid receptacle, means within the liquid in said receptacle for raising or lowering the temperature of the liquid, including a spiral heat exchange coil extending substantially the full length of the tank, a rotor having its axis parallel to the axis of the coil and having spiral vanes extending lengthwise thereof and adapted to dip in said liquid, means for drawing air through said rotor in contact with said vanes, positive means for actuating said rotor to cause the vanes to periodically dip into said liquid, whereby continuous circulation of the liquid over said coil is set up, and means for automatically regulating said actuating means according to the requirements of the air undergoing treatment.

3. An air conditioning apparatus comprising a liquid receptacle, means within the liquid in said receptacle for raising or lowering the temperature of the liquid, including a spiral heat exchange coil extending substantially the full length of the tank, a rotor having its axis parallel to the axis of the coil and having spiral vanes extending lengthwise thereof and adapted to dip in said liquid, means for drawing air through said rotor in contact with said vanes, positive means for actuating said rotor to cause the vanes to periodically dip into said liquid, whereby continuous circulation of the liquid over said coil is set up, and manual means for regulating the speed of said actuating means whereby the rate of circulation is varied as desired. 20 25 30 35

4. An air conditioning apparatus comprising a liquid receptacle, means within the liquid in said receptacle for raising or lowering the temperature of the liquid, including a spiral heat exchange coil extending substantially the full length of the tank, a rotor having its axis parallel to the axis of the coil and having spiral vanes extending lengthwise thereof and adapted to dip in said liquid, means for drawing air through said rotor in contact with said vanes, positive means for actuating said rotor to cause the vanes to periodically dip into said liquid, whereby continuous circulation of the liquid over said coil is set up, means for automatically regulating said actuating means according to the requirements of the air undergoing treatment, and manual means for regulating the speed of said actuating means whereby the rate of circulation is varied as desired. 50 55

5. An air conditioning apparatus comprising a liquid receptacle, means within the liquid in said receptacle for raising or lowering the temperature of the liquid, including a spiral heat exchange coil extending substantially the full length of the tank, a rotor having its axis parallel to the axis of the coil and having spiral vanes extending lengthwise thereof and adapted to dip in said liquid, means for drawing air through said rotor in contact with said vanes, means for positively actuating said rotor to cause the vanes to periodically dip into said liquid, whereby continuous circulation of the liquid over said coil is set up, and a thermal valve located within said liquid for regulating the flow of heat exchange fluid through said coil. 60 65 70

6. The herein described apparatus for conditioning air, comprising a housing having a water chamber therein, means for maintaining a substantially constant water level in said chamber through said coil.

- ber, an air conditioning element comprising a rotor of absorbent material partially immersed in the water in said water chamber, means for rotating said rotor, means for pulling a stream of air through and about said rotor and forcibly discharging a stream of the conditioned air from the apparatus, said water chamber having means for trapping the sludge including the particles taken from the air stream in the apparatus by the surfaces of said rotor and washed from such surfaces during travel of the parts of the rotor immersed in the water of said water chamber, and means for supplying water to said water chamber and at the same time flushing the entrapped sludge from said chamber.
7. The apparatus as set forth in claim 6, said water supplying means including a nozzle element located in said water chamber near the bottom thereof and a supply pipe for said nozzle, a valve in said supply pipe, said valve being normally closed, under electrical control, and means controlled by the level of the water in said water chamber whereby, upon lowering of the level to a certain predetermined degree, the electrical control of said valve is effected and the valve automatically opens to admit water to said nozzle element.
8. The apparatus as set forth in claim 6, said water chamber having a drain outlet, an electrically controlled, normally closed valve for said outlet, the water supplying means for said water chamber including a nozzle element located in said water chamber near the bottom thereof, a water supply pipe for said nozzle element, an electrically controlled, normally closed valve for said water supply pipe, and means controlled by the water level in said water chamber, and correlated to the electrical controlling means for both of said valves, whereby, upon lowering of the water level in said water chamber to a predetermined degree, the electrical control of said valves is effected and both of said valves open automatically and simultaneously, the drain outlet of said water chamber being proportioned to take off the sediment flushed from the chamber and the flow of the water supply through said nozzle element being under pressure and volume sufficiently to fill the water chamber more rapidly than the outflow through the drain outlet.
9. In an air conditioning apparatus of the character described, a water chamber, means for maintaining a substantially constant water level in said chamber, an air conditioning element comprising a multiple surfaced portion of absorbent material movably immersed in the water in said chamber, the several surfaces travelling in succession into, through and out of the water, means for passing a stream of air through the apparatus in contact with the surfaces of said air conditioning element after immersion and until again immersed, said water chamber having a depressed bottom portion to entrap sludge washed from said surfaces of the air conditioning element while travelling immersed, a valved water supply for said water chamber, a valved drain outlet for said water chamber, the valves for said supply and drain being normally closed, and means controlled by the water level in said chamber for automatically opening the valves of said water supply and drain outlet simultaneously when the level of the water in said chamber is lowered to a predetermined degree, the inflow of the water supply to said chamber being in greater volume than the outflow through the drain, whereby the chamber fills during the outflow and upon the water reaching the normal working level in the chamber said valves are automatically closed.
10. The herein described apparatus for air conditioning, comprising a cabinet, a water chamber in said cabinet, means for maintaining a substantially constant water level in said water chamber, an air conditioning element comprising a rotor having longitudinally extending vanes of absorbent material, said element being rotatably mounted above said water chamber so that it rotates circumferentially partially immersed in the water in said chamber, a motor for rotating said rotor, a fan for pulling a stream of air to be conditioned through the apparatus in contact with the surfaces of the vanes of said rotor after immersion and until again immersed, and for discharging the conditioned air from the apparatus, means for regulating the temperature of the water in said water chamber, said means including refrigerating coils immersed in the water and a thermally controlled refrigerating unit for said coils, said refrigerating coils and unit being selectively operable, at will, so that by adjustment of the thermal controlling means the temperature of said coils is held to a predetermined degree, heating means located in said water chamber for heating the water therein, operable at will, a thermostat located in the enclosure being air conditioned from said apparatus, and a humidistat located in said enclosure, said thermostat and said humidistat being connected with said motor which operates said rotor and being adapted to be set for a predetermined minimum temperature, as to the thermostat, and a predetermined degree of humidity content for the conditioned air, as to the humidistat, so that the motor is automatically caused to cease operating when that predetermined degree of temperature or humidity content of the conditioned air in the enclosure is reached.
11. In an air conditioning apparatus, an air conditioning element of absorbent material movable partially immersed in a water bath, said element comprising a rotor including circular end frame members each having a central hub portion and an annular outer portion, said hub portions being connected by longitudinal spaced bars and said outer annular portions being likewise connected by outer longitudinal bars, the absorbent material being arranged in the form of vanes supported on said longitudinal bars, certain of said vanes being radial from the inner or hub bars to correlated outer bars and others extending from inner to outer bars in outwardly divergent or substantially V-shape arrangement.
